UNITED STATES PATENT OFFICE.

ERNST FREDERIK HENRY ENNA, OF COPENHAGEN, DENMARK.

BUFFING MACHINE.

Application filed March 27, 1925, Serial No. 18,778, and in Great Britain August 30, 1924.

This invention relates to buffing-machines, more particularly for use in finishing the soles and heels of boots and shoes, and including an inflatable pad mounted on one end of a rotatable air-conducting spindle and provided with an abrasive cover, the pad being maintained in an inflated condition by means of a suitable air pump, adapted to force air through the spindle into the pad to inflate the same.

The object of the present invention is to provide a buffing-machine characterized as above stated, of simple construction and adapted to maintain a charge of air within the inflatable pad for a considerable time, without renewal.

To this end according to this invention, the pump for producing and maintaining the pressure in the inflatable pad comprises a piston fixed to one end of the spindle, and a cylinder slidable on the spindle and the piston, the spindle having a longitudinal air duct, and the cylinder being adapted to be reciprocated by hand so as to deliver air past a non-return valve in the duct of the spindle and thence to the interior of the pad. A relief valve is preferably provided at a convenient point in the spindle, with its stem extending through the wall thereof, whereby the pressure may be relieved when desired.

Means for securing the pad as well as its abrasive cover, to one end of the spindle, conveniently comprises an annular seat rigidly mounted on the spindle, and an annular clamping member carried and adapted to be moved longitudinally by a nut, having a screw-thread engagement with the spindle, so as to clamp an annular flange on the pad, together with the pad cover, between the clamping member and the seat.

The accompanying drawing forming a part of this specification, shows partly in elevation and partly in section, a buffing machine embodying the invention, the main portion of the supporting frame being omitted.

In the drawings, A designates a frame member or portion, adapted to be secured to a main supporting frame (not shown), by means of a rod B. The member A is provided with two bearings C and D which support a rotatable spindle E, carrying a pulley E' by means of which it is driven, the spindle being provided with a longitudinal duct E². The lower end of the spindle E carries an inflatable pad or cushion F,

preferably of rubber, adapted to back a cover of abrasive material such as sand paper, emery cloth or the like. The pad is provided with an annular flange F'. This flange and the margin of the abrasive cover are confined by attaching means including an annular seat G, fixed to the spindle, and a longitudinally movable clamping member H. The clamping member H is movable into and out of its clamping position by means of a nut H', having a groove therein engaged by a flange H² at the upper end of the tubular shank H³ of the clamping member. To the upper end of the spindle is fixed a piston K of the cup leather type. J designates a cylinder which is slidable on the spindle and piston. The cylinder J is provided with an air inlet J', below the piston K and can be reciprocated by hand, so as to force air through the duct E², into the pad F, a non-return valve L being provided in the duct to prevent the return of air to the cylinder. The valve L may be of the type usually employed in pneumatic tires, and yields or opens when the cylinder is projected toward the pad, and closes when the cylinder is retracted.

A spring M is provided serving to yieldingly arrest the upward movement or retraction of the cylinder J. The spindle is provided with an air vent between its ends, and with a spring-pressed relief valve N, the stem of which projects from the spindle and is manually movable to open the air vent and permit the escape of air to reduce the pressure in the pad.

In machines of this type it is usual to provide a duct for conveying away the dust produced by the buffing. In order that the spindle E may be adjusted so as to bring the pad F adjacent the mouth of such duct, the rod B is adapted to be clamped to its support at any point in its length.

The vertical position of the pulley E' with reference to the bearing members C and D can be varied, as for example, by reversing the sleeve on which the pulley is mounted.

The details of construction may be varied without departing from the spirit of the invention as defined by the following claims.

I claim:

1. In a buffing machine, the combination of a tubular rotatable spindle, an inflatable pad secured to one end of the spindle and communicating with the bore thereof, a piston secured to the other end of the spindle

and provided with a continuation of the spindle bore, a manually movable pump cylinder into which the piston and adjacent end of the spindle extend, said cylinder being adapted to be reciprocated over the piston and spindle in the direction of the length of the spindle, a non-return valve within the air duct adjacent the piston, the spindle having an air vent opening through its wall at a point between the inflatable pad and the pump cylinder, and a spring pressed valve normally closing said vent and having its stem extending laterally outward from the spindle.

15. 2. In a buffering machine, the combination of a tubular rotatable spindle having an outwardly projecting annular flange at one end and having a section of its body adjacent said flange exteriorly threaded, an inflatable

pad having a portion of its casing extending 20 inward over said flange on the spindle, an annular clamping member surrounding the spindle and having one end adapted to clamp the pad casing against the flange at the end of the spindle and its opposite end 25 provided with a flange, a nut engaging the threaded section of the spindle, and having an interior groove engaging the flange on the clamping member whereby the clamping member will be positively moved both toward and from the pad as the nut is rotated, and means communicating with the interior of the spindle for forcing air into the pad to inflate the latter.

In testimony whereof I have affixed my 35 signature.

ERNST FREDERIK HENRY ENNA.
